UNITED STATES PATENT OFFICE.

JOHN B. FREYSINGER, OF STAMFORD, CONNECTICUT, ASSIGNOR TO THE YALE & TOWNE MANUFACTURING COMPANY, OF STAMFORD, CONNECTICUT.

PADLOCK.

Application filed March 5, 1923. Serial No. 622,953.

To all whom it may concern:

Be it known that I, JOHN B. FREYSINGER, a citizen of the United States, and a resident of Stamford, in the county of Fairfield and State of Connecticut, have invented certain new and useful Improvements in Padlocks; and I do hereby declare the following to be a full, clear, and exact description of the invention, such as will enable others skilled in the art to which it appertains to make and use the same.

This invention relates to improvements in padlocks and more particularly to those of the adjustable shackle type.

Heretofore it has been proposed to secure the shackle of a padlock in adjusted position relatively to the lock casing with the use of key controlled ratchet means, the pawl of the ratchet being spring-pressed and adapted to ride over the teeth formed by a series of notches in the side of the shackle as the latter is pushed into the casing and snap into said notches.

One object of my present invention is to provide simple and efficient friction clutch devices for securing the shackle against outward movement from any position to which it may have been adjusted relatively to the casing of the lock, and to provide means whereby said clutch devices may be manipulated with the use of a proper key to release the shackle.

With this and other objects in view, the invention consists in certain novel features of construction and combinations of parts as hereinafter set forth and pointed out in the claims.

In the accompanying drawings,—

Figure 1 is a vertical section partly in elevation of a padlock showing one embodiment of my invention.

Figure 2 is a transverse sectional view of the same, and

Figures 3, 4, 5, 6, 7, 8, 9, 10, 11 and 12 illustrate various modifications.

In the drawings, 1 represents the casing of a padlock and 2 the shackle,—the legs of the latter being adapted to pass through the casing 1. The legs of the shackle may have an approximately semi-circular cross-section so as to present flat inner faces 2^a as indicated in Figures 2 and 4.

A key actuated device such, for example, as a cylinder lock of the pin tumbler type, 3, is suitably secured within the casing 1

and its revoluble member 4 is provided at one end with a cam head 5 for a purpose hereinafter explained.

Friction clutch members 6 are eccentrically mounted within the casing 1 or preferably within a frame 7 located in said casing,—said clutch members being so positioned that they may engage the inner flat faces of the shackle legs. Each clutch member 6 is provided with a lug or projection 8 and these engage the cam head 5 carried by the revoluble member 4 of the key operated means. Springs 9 press against lugs or projections 8 in a manner to turn the eccentric clutch members 6 and cause them to clamp against the shackle legs and hold the shackle against outward movement. With the use of a proper key, the revoluble member 4 of the key operated means may be turned to impart rotary motion to the cam head 5 and cause the latter to operate the eccentric clutch members in a manner to release the shackle.

Instead of providing springs to force the clutch members into clutching action, this may be accomplished by a grooved cam head 10 carried (through the medium of a spring 9^a) by the revoluble member 4 of the key operated means as shown in Figures 3 and 4,—such cam head serving to move the clutch members both into and out of clutching relation to the shackle.

In the embodiment of the invention shown in Figures 5 and 6, eccentric clutch members 11 are provided and formed with serrated portions 12 to engage the shackle legs and springs 13 are employed for turning the clutch members in a direction to cause them to clutch the shackle legs,—said springs being coiled about the journals 14 of the clutch members and having ends bearing respectively against the casing 1 and the lugs or projections on the clutch members.

In the embodiment of the invention shown in Figures 7 and 8, the shackle legs 14 are made fluted or corrugated and the clutch members 15 have an oval shape and are adapted at their smaller ends to engage the fluted shackle legs 14 in a manner to prevent outward movement of the shackle. The clutch members 15 are provided with lugs 16 which enter a cam groove 17 in a head 18 carried by the revoluble member 4 of the key actuated means, so that when said head 18

is turned (with the use of a key) in one direction, the clutch members will be moved in a direction to clutch the shackle and when moved in the reverse direction to unclutch the shackle.

In the embodiment of the invention shown in Figures 9 and 10, the legs 19 of the shackle are made slightly fluted and the clutch members 20 are provided with serrated portions 21 which are eccentric to the axis of the respective clutch members to engage the fluted shackle legs 19.

It will be observed that in the construction shown in Figure 9, the clutch members 15 are moved to clutching position by the action of springs 9 substantially as shown in the construction illustrated in Figure 1 and said clutch members are moved to unclutching position to release the shackle, by means 20 of a cam head 22 carried by the revolute member 4 of the key operated means.

The construction shown in Figures 11 and 12 is quite similar to that shown in Figures 9 and 10,—the principal difference being that in the construction shown in Figures 11 and 12 the clutch members are moved in both directions by a cam head 23 carried by the revolute member 4 of the key actuated means, while in the form shown in Figure 30 9, the clutch devices are moved to clutching position by the action of the springs 9.

Having fully described my invention what I claim as new and desire to secure by Letters-Patent, is:—

35 1. In a padlock, the combination with a casing and a sliding shackle, of a cam member pivotally mounted in the casing and engageable with a leg of the shackle, a spring normally pressing said cam member in a direction for cooperative relation to the shackle leg, and key operated means cooperable with said cam to move it in the opposite direction to release the shackle.

40 2. In a padlock, the combination with a casing and a sliding shackle, of a pivoted cam member cooperable with a leg of the

shackle to clutch the same, said cam member having a projecting part, a spring normally pressing said cam member in a direction to clamp the shackle leg, and key actuated cam means cooperable with the projecting part on said cam member to move the latter toward releasing position.

3. In a padlock, the combination with a casing and a shackle, of an eccentric clutch pivotally mounted in the casing and cooperable with the shackle by engagement with the inner face of a member thereof to hold the shackle against outward movement, and key actuated means cooperable with said pivoted eccentric clutch to move the same to release the shackle.

4. In a padlock, the combination with a casing, a shackle adjustable therein, and a key actuated device, of eccentric clutch members pivotally mounted in said casing and cooperable with the shackle to hold the same against outward movement, and a cam device carried by a movable part of the key actuated device to move said eccentric clutch members.

5. In a padlock, the combination with a casing, a shackle having legs adjustable in said casing and key controlled means, of eccentric clutch devices pivotally mounted in said casing and cooperable with the legs of the shackle to prevent outward movement of the latter, springs normally operating to move said clutch devices into clutch relation to the legs of the shackle, and a cam device carried by the movable member of the key controlled means and cooperable with the eccentric clutch devices to move the same to unclutching position for releasing the shackle.

In testimony whereof, I have signed this specification in the presence of two subscribing witnesses.

JOHN B. FREYSINGER.
